PROCESS FOR THE PRODUCTION OF
TOLUOL

George Edward Liedholm, Long Beach, and

Calif., a corporation of Delaware

Application June 10, 1940, Serial No. 339,732

7 Claims. (Cl. 260—668)

The present invention relates to a process for the production of toluol from naphthenic distillates. An object of the invention is to provide a method whereby commercial grades of toluol suitable for nitration, solvent use, and the like may be produced in a most economical manner from available naphthenic hydrocarbon fractions of natural and/or synthetic origin.

Toluol is one of the primary compounds upon which aromatic chemistry is based. It is employed in large quantities as a starting material for the synthesis of a great variety of useful products such as dyestuffs, explosives, drugs, flavors, perfumes, photographic developers, plastics, intermediate chemicals, and many others. Virtually the only source of toluol is, however, a by-product from the distillation of coal, being recovered in a yield of about 0.00125% based on the coal treated or about 0.25% based on the coal-tar obtained. Consequently, the supply of toluol is primarily dependent upon the condition of the steel and coal-tar industry and is in any case limited. Aside from the numerous uses where its application is more or less obligatory, toluol has a great many potential uses which have been curtailed by its limited supply and relatively high price. As a consequence considerable attention has been given to the possibility of producing toluol from other sources.

This problem has been considered from two angles. The first of these is to recover toluol from aromatic petroleum fractions, particularly cracked distillates. It is known that distillates from certain petroleums and most highly-cracked distillates contain appreciable quantities of aromatic hydrocarbons from which it is possible to recover highly aromatic distillates and even relatively pure aromatic hydrocarbons by a suitable combination of steps involving fractionation and extraction. The recovery of toluol from such distillates is, however, quite difficult and has not proven to be economical. In the first place, only a small proportion of the aromatic hydrocarbons in these distillates is toluol, and consequently, large quantities of material must be processed to recover relatively small yields. Furthermore, the toluol in these distillates, even after a preliminary close fractionation, is present in an extremely complicated mixture of hydrocarbons from which it is most difficult to separate a toluol of satisfactory purity. For some applications, such in particular as its use as a solvent, pure toluol is not necessary. For most of its applications, however, particularly where it is used as a starting material in various chemical syntheses, toluol of

at least 98% purity is demanded. One of the major uses of toluol, for example, is in the production of T. N. T. Toluol for this purpose must be water-white, have a boiling range of not more than 1° C., and have a specific gravity at 15.5/15.5° C. between 0.866 and 0.874. It must furthermore pass the standard sulphuric-acid wash test which means that it must be free of all but the minutest traces of olefine hydrocar-

10 bonds and other impurities which are normally present in considerable quantities in the parent petroleum distillate. It is known that during the World War T. N. T. was produced from relatively impure toluol fractions obtained from petroleum distillates. This, however, necessitated executing the nitration step-wise with intermediate treatments for the removal of the impurities and was only resorted to due to the emergency at the time. While toluol of sufficient purity can be 15 separated from cracked distillates if the separation and purification processes are carried far enough, the low yields obtained and the expense of the recovery generally make such processes impractical for commercial application.

20 25 The other approach to the problem is the synthesis of toluol from non-aromatic hydrocarbons. It has long been known that hydroaromatic hydrocarbons may be catalytically dehydrogenated to aromatic hydrocarbons. Thus, it has been shown in the laboratory that toluol may be easily 30 produced from methylcyclohexane by catalytic dehydrogenation. While this has long been known it has not led to the commercial production of toluol due primarily to the lack of a suitable 35 source of methylcyclohexane. It is known that certain naphthenic distillates contain appreciable quantities of methylcyclohexane. Here again, however, the small yields and difficulty of separation of a commercial grade of toluol detract from the practicability of the process.

40 45 Quite recently it was discovered that cyclic hydrocarbons can be produced catalytically from open-chain hydrocarbons by a new reaction now known as cyclization. Thus, it has been shown by laboratory experiments that fair yields of toluol may be produced from normal heptane, 2-methylhexane, 3-methylhexane and the corresponding olefines. The preparation of toluol from these open-chain hydrocarbons may be effected 50 catalytically by passing vapors of the hydrocarbon over a cyclization catalyst under appropriate conditions whereby a simultaneous dehydrogenation and ring-closure takes place. It is thus seen that, starting from petroleum, toluol may 55 be potentially produced from three sources: (a)

recovery of naturally-occurring toluol, (b) formation of toluol from methylcyclohexane, and (c) formation of toluol from paraffinic hydrocarbons (n-heptane, 2-methyl hexane, and 3-methyl hexane) by cyclization-dehydrogenation.

According to the process of the present invention the larger part of the toluol is usually produced by the dehydrogenation of methylcyclohexane. The process, however, does not rely solely upon the small amount of methylcyclohexane occurring naturally in the hydrocarbon feed. Additional amounts of this hydrocarbon are produced in the process from the other hydrocarbons. The process is also adapted to recover substantially all of any toluol naturally present in the feed. Moreover, the process is adapted to allow the production of additional amounts of toluol by catalytic cyclization. As a result, the process of our invention is unique in the exceptionally high yields of toluol obtained.

According to the process of the invention, we produce toluol from naphthenic distillates. By naphthenic distillates we mean hydrocarbon distillates of natural or synthetic origin, containing an appreciable quantity of naphthenic and paraffinic hydrocarbons having seven carbon atoms in the molecule. Suitable naphthenic distillates are obtained from a large number of crude petroleums. A few typical crudes from which suitable naphthenic distillates may be obtained are, for example, Los Angeles Basin crude, Huntington Beach crude, Dominguez Hill crude, Ventura crude and El Capitan crude. The naphthenic distillate is preferably fractionated to separate a narrow cut containing the larger part of the hydrocarbons having seven carbon atoms in the molecule. Such a fraction may, for example, boil between about 190° F. to 230° F. The boiling points of these convertible paraffin hydrocarbons are:

	° F.
Normal heptane	209.2
2-methylhexane	194
3-methylhexane	197.3

This fraction, if from a naphthenic distillate, also contains substantially all of the methylcyclohexane (boiling point 213° F.) present. These naphthenic distillates also usually contain a small but significant amount of toluol. Any toluol naturally present in the distillate is also included in such fractions. The advantages of the use of such a fraction are fourfold. First, the fraction represents a practical proportion of the material to be treated. Second, when the fraction is subjected to an appropriate dehydrogenation-cyclization treatment toluol is produced both by dehydrogenation of the methylcyclohexane as well as cyclization of the open-chain paraffins, and considerably increased yields are produced. Third, any toluol naturally present in the distillate is recovered. Fourth, the proportion of toluol in the product from the dehydrogenation-cyclization treatment being larger, the difficulties and expense of recovering the toluol are reduced.

A suitable method for the separation of such a fraction is illustrated in the attached Figure 1. Referring to Figure 1, it is seen that the naphthenic oil is fed to a still wherein all material boiling below the initial boiling point of the desired fraction is removed overhead. The bottoms from this still pass to a second still wherein the desired fraction is taken off overhead. The quantity of this fraction will vary according to the character of the distillate, but in most cases

will be a sizable fraction. Typical analyses of these fractions from such crudes are for example:

	By weight
Aromatic hydrocarbons	1-10
Naphthenic hydrocarbons	15-75
Paraffin hydrocarbons	25-85

It is not practical, however, to produce toluol directly from such naphthenic fractions. This is due primarily to the fact that when subjecting such commercial fractions to a catalytic dehydrogenation-cyclization treatment the active life of the catalyst is very short. This requires frequent stopping of the reaction and reactivation of the catalyst. The reactivation treatment, which is effected by carefully burning deposited carbonaceous material from the catalyst under controlled conditions, greatly decreases the economy of the process since it is time-consuming, causes loss of material, causes a gradual permanent loss of the catalyst activity, and requires the handling of large quantities of reactivating and flushing gases. The results obtained upon subjecting such fractions to a conventional dehydrogenation treatment are illustrated by the following example:

Example I

A straight run naphthenic gasoline was fractionated to prepare a 190-230° F. heart cut. A detailed investigation of its composition showed that it contained C₇ components in the following volume ratios:

35	Dimethyl cyclopentanes	1.1
	Methyl hexanes	0.6
	Methyl cyclohexane	1.0
	n-Heptane	0.5
40	Toluol	0.3

This material was subjected to a catalytic dehydrogenation-cyclization treatment under the following conditions:

45	Catalyst=chromium oxide supported upon activated alumina (11% Cr)
	Temperature=975° F.
	Time=6 hours
	Space velocity=0.73 vol. liquid/vol. catalyst/hour
50	Pressure=15 lbs./sq. in. exit pressure

Pure n-heptane, or pure methylcyclohexane, or a synthetic mixture of pure n-heptane and pure methyl cyclohexane, when heated under these conditions, give excellent yields of toluol with little formation of carbon and gas. The above fraction, however, afforded a conversion to toluol of only about 7% to 10% (i. e. 15% to 17% toluol in the product). Moreover, the carbonaceous material deposited on the catalyst amounted to 4.6% by weight of the feed treated, and approximately 13% by weight of the feed was converted to gases. Under optimum conditions it required about 4 hours to regenerate the catalyst.

According to the process of the present invention, not only are the yields of toluol obtained from any given naphthenic distillate much greater, but the decline in the catalytic activity of the catalyst is much slower and less time is required for regeneration, and a crude toluol is produced from which commercial grades of toluol may be recovered more economically.

It is found that the above-described fractions from naphthenic distillates invariably contain

considerable quantities of alkylated cyclopentanes, such in particular as:

	Boiling point, ° F.
1,1-dimethylcyclopentane	189.5-191.3
1,3-dimethylcyclopentane	195.3
1,2-trans-dimethylcyclopentane	197.2

Other hydrocarbons which are usually found to be present to various extents, include:

	Boiling point, ° F.
3,3-dimethylpentane	186.8
2,3-dimethylpentane	193.5
3-ethylpentane	199.9
Propylcyclobutane	210.2-212
2,2,4-trimethylpentane	210.7

These latter hydrocarbons when present act primarily as inert diluents and are only detrimental insofar as they make the recovery of the toluol more difficult. The above-mentioned alkyl-cyclopentanes, on the other hand, are found to be very detrimental. When present, even in quite small quantities in the hydrocarbon fraction to be treated, they cause a rapid deterioration of the activity of the catalyst. It is found that if these detrimental alkylcyclopentanes are removed, the active life of the dehydrogenation-cyclization catalyst is greatly improved, much less frequent reactivation of the catalyst is required, and the process is made much more economical. According to the process of the present invention, these detrimental-acting dimethylcyclopentanes are not only removed from the hydrocarbon fractions to be treated, but they are converted into toluol, thus materially increasing the yield. The removal of these poisoning dimethylcyclopentanes is effected by subjecting them to a suitable isomerization treatment whereby they are converted to a large extent to methylcyclohexane.

If a hydrocarbon fraction from a naphthenic distillate, boiling for example between 190° F. and 215° F., is subjected to an isomerization treatment, it is found that a certain improvement in the yield and economy of the process results. Far greater improvements may be obtained, however, if the hydrocarbon fraction is first separated into two fractions, one containing the larger part of the normal heptane and methylcyclohexane and the other containing the larger part of the dimethylcyclopentanes and the methyl hexanes, and subjecting to the isomerization treatment only the latter. There are several reasons, we have found, why this method is superior. By separating the hydrocarbon to be treated into two such fractions, for example boiling between 200° F. to 230° F. and 190° F. to 200° F. respectively, the amount of material to be processed by isomerization is materially less; the considerable quantities of normal heptane present are not subjected to the isomerization treatment and are therefore not partially isomerized to branched-chain isomers from which toluol cannot be produced; a greater conversion of the dimethylcyclopentanes to methylcyclohexane is achieved; and a portion of the dimethylpentanes, if present, is isomerized to methyl hexane which is then available for the production of toluol. This not only effects a more thorough removal of the poisoning dimethylcyclopentanes but also accounts for a further increase in the yield of toluol. Due to the much more efficient elimination of hydrocarbon types not directly convertible to toluol by cyclization-dehydrogenation, this method of operation also materially decreases the difficulty and the expense of the subsequent toluol recovery and

makes it possible to recover toluol of excellent purity in an economical manner.

The process of our invention, then, in its more general aspect comprises separating a naphthenic distillate to be treated into two fractions, subjecting the lower-boiling fraction to an isomerization treatment, subjecting the fractions to a dehydrogenation-cyclization treatment, and recovering toluol from the thus-treated product.

10 This is illustrated diagrammatically in the attached flow diagram, Figure 1. The narrow C-7 cut from the naphthenic distillate is separated into a lower and a higher boiling fraction as described above. Thus, in the attached flow diagram the desired fraction to be treated is passed to a third still wherein it is separated into a lower and a higher boiling fraction. While in the above we have explained the process in terms of two separate distillations, i. e. first separating a C-7 cut, boiling for example between 190° to 230° F., and later separating this fraction into a higher and lower boiling fraction, it is of course obvious that the same result may be obtained directly by separating two cuts of suitable boiling range. 15 Very suitable boiling ranges for these fractions are, for example, 190° to 200° F. and 200° F. to 230° F. respectively. This separation may likewise be effected by any of the conventional methods. In general the transition boiling point 20 between the two cuts is about 200° F.; for instance, from about 196° to about 208° F. The initial boiling point of the lower cut may vary considerably, for example from about 170° F. up to about 195° F. If the initial boiling point 25 is chosen much below 190° F. considerable non-convertible hydrocarbons are included which increase the amount of the material to be processed and make the separation of a pure toluol more difficult. On the other hand, if the initial boiling point is chosen much above 190° F., a loss in toluol yield results. In general, the initial boiling point of the lower-boiling fraction is chosen at about 190° F., for example 180° to 195° F. The upper range of boiling point of 30 the higher-boiling fraction is preferably chosen somewhat about 210° F., for example 214° to 240° F. Although higher-boiling material may be included in the fraction, its presence is in general undesirable since it makes the recovery of pure 35 toluol more difficult.

40 According to the present process the lower boiling of these two fractions is subjected to an isomerization treatment. This may be effected by contacting the fraction in the liquid or vapor phase, preferably in the liquid phase, under suitable conditions with an isomerization catalyst, a hydrogen halide promoter, and, if desired, hydrogen. Preferable isomerization catalysts are those comprising anhydrous aluminum chloride and/or aluminum bromide. Of these, aluminum chloride is preferred since it is less expensive, easier to employ and has much less tendency than aluminum bromide to cause degradation of the naphthenic hydrocarbons. Other acid-acting 45 catalysts of the Friedel-Crafts type such as the halides of Zr, Zn, Sn, Be, Nb, Ta, Sb, B, Cu and Cd may also be employed if desired in conjunction with the aluminum chloride. The catalyst may, if desired, be employed as a solid either in suspension in the liquid reaction mixture or as a fixed bed. In the latter case it is preferably employed as lumps, granules or pellets of suitable size, preferably deposited upon or mixed with a suitable solid support. Particularly effective 50 catalysts are produced when aluminum chloride 55 is employed in conjunction with aluminum bromide. 60 The isomerization treatment may be conducted at temperatures ranging from about 100° to 300° F. and at pressures ranging from about 100 to 1000 pounds per square inch. The reaction time may be from about 10 minutes to 24 hours. 65 The catalyst may be recovered by any suitable 70 method, for example by separation of the liquid reaction mixture into two layers, the lower layer containing the catalyst which is then washed and dried. The catalyst may be 75 recovered and reused.

is supported upon or intimately mixed with one of the various preferably adsorptive siliceous and/or aluminous materials of natural or synthetic origin which contain an appreciable amount of firmly-bound water. Suitable materials of this category are, for example, the naturally-occurring minerals and clays such as pipe clay, bauxite, fuller's earth, bentonite, Florida earth, meerschaum, kaolin, infusorial earth, kieselguhr, diatomaceous earth and the like; the various treated clays and clay-like materials; and artificially prepared materials such as "Activated-Alumina," silica gel, the artificial permutites and the like. These materials are preferably heated in a dry atmosphere at a moderately elevated temperature, such, for instance, as about 200° to 300° C., until they substantially cease to give off water. Although these materials produce preferred catalysts when combined with aluminum chloride, other supporting materials such as activated carbon, coke, crushed brick, pumice and the like may also be used.

While solid catalysts may be suitably employed we have developed an improved and advantageous method whereby the isomerization treatment may be effected in a continuous manner using liquid catalysts. Particularly suitable liquid catalysts are those of the Gustavson (C. 1903 II 1113) and Ansolvo (German Patent No. 535,473) acid types wherein aluminum chloride is in combination with various organic compounds such as organic acids, ethers, esters, hydrocarbons, etc., and those of the metal double-salt type in which the aluminum chloride is in loose combination with similar metal halides such, for instance, as the halides of Sb, Sn, Zr, Cu, Ti, Na, K, Li and the like. By employing aluminum chloride in combination with certain of these metal halides, excellent isomerization catalysts may be prepared which melt to free-flowing liquids at very moderate temperatures and may be pumped through the reaction system with or counter-current to the hydrocarbon fraction to be isomerized. The use of liquid catalysts in the isomerization has definite advantages. The naphthenic distillates to be treated often contain small amounts of aromatic and/or olefinic hydrocarbons. These hydrocarbon types, if present, are generally quite detrimental when employing fixed beds of catalysts. When employing fluid catalysts, hydrocarbon fractions containing small amounts of olefines and/or aromatic hydrocarbons may be treated without difficulty. These liquid catalysts moreover have a considerably milder action and in general are much less prone to cause degradation of the naphthenic hydrocarbons. Also, they allow the isomerization to be effected in simple apparatus in a continuous most practical manner. A flow diagram of a suitable isomerization unit employing this principle is illustrated in the attached Figure II. Referring to Figure II, the hydrocarbon to be treated is fed from a storage tank 1 via pump 2 to a circulating pump 3 wherein it is mixed with a liquid catalyst and promoter and circulated through a heater 4 and time tank 5, and back to the circulating pump 3 via a valved line 6. The time tank 5 is preferably equipped with perforated baffles or other means to insure thorough contact with the hydrocarbon and liquid catalyst. All or a portion of the material passing through time tank 5 is withdrawn to a separating device 7 wherein the liquid catalyst is separated from the bulk of the hydrocarbon. The liquid catalyst from separator 7 is recycled to the circulating

5 pump 3 via a line 8. A portion of the partially-spent liquid catalyst may be continuously or intermittently removed if desired via valved outlet 9 and an equivalent amount of fresh catalyst 10 may be added via pipe 10. The hydrocarbon from separator 7 is passed through a cooler 11 and filter 12 to remove any globules of suspended catalysts and is then passed to tank 13.

10 The assembly of apparatus illustrated diagrammatically in Figure II is adapted for the use of liquid catalysts of the above-mentioned Gustavson or Ansolvo acid types. The catalyst may be prepared in any conventional manner and supplied to the system, for instance, via line 10. 15 For the sake of completeness provision is also made for the preparation of the catalyst in the flow diagram of Figure II. This apparatus, which may be considerably modified if desired, comprises a mixing vessel 14 interconnected in a circulatory system via circulating pump 15 to a small chamber 16. Aluminum chloride or other catalysts are charged to the mixing vessel 14 and a quantity of the organic material to be reacted therewith to form the complex catalyst is introduced via line 17. This may be any one or a mixture of a great number of organic compounds. In case the complex catalyst is one of the Gustavson type (C. 1903 II 1113) the liquid added may be an aromatic hydrocarbon or a hydrocarbon mixture rich in aromatic hydrocarbons. Aromatic hydrocarbons, as a class, are generally suitable. Thus, for example, benzol and the various alkyl derivatives thereof may be used. Particularly suitable catalysts of this type 20 may be prepared from the so-called bright-stocks or Edeleanu extracts obtained by the extraction of aromatic-containing distillates with sulphur dioxide. These catalysts are found to contain approximately twice as much aluminum chloride, for example, as catalysts of the same general type prepared from benzol or toluol. They therefore have a much longer life. Catalysts of this type 25 are described in United States Patents Nos. 1,671,517, 1,586,357, 1,999,345, and British Patent No. 7,112 (1914). Aromatic extracts obtained by extraction with other selective solvents may 30 of course, likewise be employed.

35 The isomerization treatment is preferably executed in the presence of a hydrogen halide promoter such, for example, as hydrogen chloride. The amount of promoter preferably employed depends upon the activity of the catalyst and the prevailing temperature, and may vary from a small amount such as about 0.05% up to several percent. In one preferred method of operation, 40 wherein the hydrocarbon fraction is treated in a continuous manner in the liquid phase, a considerable excess of hydrogen chloride (for example, a partial pressure of hydrogen chloride vapor of at least 1 to 3 atmospheres) is employed and the hydrogen chloride is recycled through the reaction zone. Thus, in Figure II the product from tank 13 is forced via pump 18 to a stripping column 19 wherein the HCl promoter and any other lower-boiling material is taken off overhead. The overhead fraction is passed through a cooler 20 into a vessel 21. Condensed liquid in vessel 21 is pumped back to the stripping tower to serve as reflux. The bottom product from 45 tower 19 is passed through a caustic scrubber 22 to remove any last traces of promoter and is then stored in tank 23. The hydrogen chloride promoter separated from the product in the stripping column is recycled back to the isomerization system via line 23. The hydrogen halide (and

hydrogen, if this is used) recycled to the system is preferably passed through a drier 26 containing a suitable drying agent such as CaCl_2 , P_2O_5 , activated-alumina, or the like. Small amounts of excess gas may be vented from time to time by valved outlet 21. Make-up hydrogen chloride is supplied to the system from any convenient source such as a high-pressure cylinder 24. As pointed out above, however, when using liquid catalysts the isomerization process may be executed with only very small amounts of hydrogen chloride promoter, for instance, less than 1%. In such cases, it may be more economical not to attempt to recover and recycle the promoter. In this case the product from tank 13 may be simply caustic-washed and sent to storage. Instead of feeding in hydrogen halide per se, the hydrogen chloride or other hydrogen halide promoter may be carried to the reaction zone, dissolved in one of the reactants, or may be generated in the reaction zone from added materials which under the reaction conditions react or decompose to liberate hydrogen halide. Suitable materials which may be added for this purpose are, for example, organic halides such as organic alkyl halides, organic hydroxy compounds such as the various phenols and alcohols, inorganic salts containing molecularly-bound hydrogen halide such as $\text{PbSO}_4 \cdot 2\text{HCl}$, $\text{CuSO}_4 \cdot 2\text{HCl}$ and the like.

The isomerization may be effected over a wide range of temperatures depending upon the space velocity, concentration of promoter employed and upon the activity of the catalyst. Although temperatures ranging from about room temperature up to about 400° F. may be employed, the isomerization may be effected economically at quite moderate temperatures such, for example, as from about 100° F. to 200° F. In some cases, especially when the catalyst is particularly active or the temperature is somewhat high, it may be found that the isomerization is accompanied by appreciable amounts of side reactions. This may be easily remedied if it occurs by slightly decreasing the temperature or concentration of promoter, or if desired, by effecting the isomerization treatment in the presence of hydrogen. Hydrogen, if employed, may be conveniently recycled with the hydrogen halide promoter. Although the use of hydrogen is not generally necessary, provision for its use is shown in Figure II. Thus, if hydrogen is recycled along with the promoter, make-up hydrogen may be added from cylinder 25.

The isomerization of naphthenic fractions, according to the above-described method, is illustrated in the following examples:

Example II

A C-7 fraction such as described above was separated into two fractions, the lower of which boiled between 182° and 204° F. This narrow fraction was subjected to an isomerization treatment with a continuously recirculated liquid catalyst under the following conditions:

Temperature=175° F.

Pressure=48 lbs./sq. in.

HCl promoter=5.2% by weight (recycled)

Ratio of liquid catalyst to hydrocarbon circulated=0.77

Contact time=1.75 hours

The catalyst was prepared by combining technical aluminum chloride with about 0.6 part by weight of a kerosene extract containing about

63% of aromatic hydrocarbons. The feed contained about 47% of dimethylcyclopentanes; in the isomerization, 39% (or 83% of this) was converted to methylcyclohexane.

Example III

The same naphthenic hydrocarbon fraction was isomerized with the same catalyst under the following conditions:

- 10 Temperature=175° F.
Pressure=40 lbs./sq. in.
HCl promoter=2.3% by weight
Ratio of liquid catalyst to hydrocarbon recirculated=0.62
15 Contact time=15 minutes

The conversion to methylcyclohexane was 78%.

Example IV

The naphthenic hydrocarbon fraction described in Example II was isomerized using the same catalyst in a stirring autoclave under the following conditions:

- Temperature=175° F.
25 Pressure=100 lbs./sq. in. and 15 lbs./sq. in.
HCl promoter=0.05% by weight (not recycled)
Ratio of catalyst to hydrocarbon=1:1
Contact time=15 minutes
Stirring=150 R. P. M.

30 This treatment was carried out for 172 hours with the same catalyst without any noticeable decline in the catalytic activity and with an average production of methylcyclohexane of 34%.

After subjecting to the isomerization treatment, 35 the fraction may, if desired, be subjected to a fractional distillation to remove small amounts of higher-boiling products which are sometimes formed in the treatment by traces of side reactions such as polymerization, alkylation, etc. and/or any lower-boiling unisomerized material. The amount of products of side reactions is usually small and the extra fractionation step may often be omitted without ill effects. According to a preferred embodiment of the invention, the 40 benefit of the subsequent fractionation to remove unisomerized material as well as any higher-boiling products is realized without the necessity of providing separate fractionating columns by blending back the isomerized product (isomerate) with the naphthenic hydrocarbon feed. Thus, the isomerate may be blended with the feed to the first, second, or third fractionating column illustrated in Figure I. This also has the 45 advantage of causing any unconverted material from the isomerization step to be recycled through that step. In the flow diagram of Figure I this optional recycle and fractionation step is indicated immediately following the isomerization step in broken lines.

The lower-boiling fraction, after being subjected to the isomerization treatment, and the above-described higher-boiling fraction are then subjected to the dehydrogenation-cyclization treatment in the usual manner. This may be most practically effected in one apparatus employing the recombined fractions, but it may also be effected separately with each fraction if, for any reason, this is desired. The dehydrogenation treatment may be effected by any of the conventional methods, using any of the conventional dehydrogenation and/or cyclization catalysts. In general, however, the dehydrogenation-cyclization treatment is effected by passing the vapors of the hydrocarbon through a reaction

zone containing a bed of catalyst and maintained under suitable reaction conditions. The optimum reaction conditions depend upon the catalyst employed and may vary considerably. In some cases, for example, such as when employing a catalyst composed of nickel and tungsten sulfides, the reaction is preferably executed under a considerable hydrogen pressure, for example, from 20 to 100 atmospheres. In other cases, for example, when employing a catalyst comprising an oxide of a metal of the 4th, 5th or 6th group of the periodic system, the process is preferably executed under about atmospheric pressure, for example, from 1 to 4 atmospheres, with a mol ratio of hydrogen ranging from 0 up to about 8, depending upon the temperature activity of the catalyst, space velocity, etc. Likewise, the temperature may vary considerably. Temperatures in the order of 900° to 1100° F. are, however, generally most suitable.

The products obtained from the dehydrogenation-cyclization treatment, according to the present process, are generally much higher in toluol and much lower in undesirable hydrocarbon impurities than those obtained from other methods. In many cases it is of sufficient purity to be used without further purification as a solvent and the like where a toluol of high purity is not required. An advantage of the present process is that the toluol may be recovered from the product in almost any desired degree of purity by relatively simple methods and with greater efficiency and economy. This is due largely to the fact that a considerable proportion of the contaminating impurities have been converted into toluol. Thus, it is generally possible to produce almost a complete yield of toluol meeting the stringent requirements for nitration by a simple extractive distillation. In some cases a wash with dilute sulphuric acid may be required.

The recovery of toluol of the desired purity may be effected by any one or combination of conventional methods such as fractional distillation, azeotropic distillation, solvent extraction, extractive distillation, crystallization, or the like. Extractive distillation, being both highly effective and economical, is a preferred method. A suitable recovery unit employing extractive distillation is illustrated in the flow diagram of Figure III. Referring to Figure III, the toluol-containing material from the dehydrogenation unit is fed to a fractionating column 51, provided with condenser 52, collector 53, and means 54 for returning a part of the overhead material to establish reflux. Fractionating column 51 is adjusted to remove the greater part of the non-converted and lighter-boiling hydrocarbons. This lighter overhead fraction may be disposed of for other purposes such as motor fuel or may, depending upon its composition, be recycled. If it consists largely of open-chain paraffins including normal heptane, it may be recycled through the dehydrogenation-cyclization unit. If, as is sometimes the case, it also contains any appreciable quantities of alkyl cyclopentanes, it is preferably recycled through the isomerization treatment. The recycling of this material being optional is indicated in flow diagram Figure I in broken lines. The bottom product from fractionating column 51 may be subjected directly to the extractive distillation treatment. However, it is often advisable to first remove a relatively pure toluol fraction in a second fractionating column 55. The bottom product from column 55 consists of small amounts of higher-boiling impurities. This is withdrawn

via line 56. The toluol fraction from column 55, after passing through the cooler 57 and collector 58, is pumped via pump 59 and line 60 to a column 61 adapted for extractive distillation. A suitable polar agent is fed at a suitable point near the top of the column in regulated quantity via pipe 62 and automatic control means 63. The polar agent employed in the extractive distillation may be any one of the many polar solvents having a preferential solubility for toluol and preferably having a boiling point of at least 220° F. Particularly suitable polar agents for this purpose are cresylic acid and other higher-boiling alkyl phenols, anilin, furfural, carbital, antimony trichloride, and the like. Hydrocarbon impurities are removed overhead from column 61 via pipe 64. The bottom product from column 61 containing the toluol and the polar agent is then fed to a fractionating or stripping column 65 wherein the toluol is separated from the polar agent. Substantially pure toluol is removed overhead via cooler 66, collector 67, and is led to storage or to a dilute acid treatment via pipe 68. The polar agent is recovered as a bottom product via pipe 69. It may be sent to storage and re-used in column 61. Further details regarding extractive distillation may be found in French Patent No. 815,302.

In the foregoing we have explained our invention in considerable detail indicating various preferred embodiments as well as certain modifications thereof. Numerous other suitable modifications, many of which may afford slightly more economical operation under certain circumstances, will at once be apparent to those skilled in the art. It is therefore to be understood that the invention is not limited to the exact form or forms described and that all such modifications as fall within the spirit of the invention are intended to be embraced in the language of the accompanying claims.

We claim as our invention:

1. In a process for the production of toluol from naphthenic straight run gasolines via catalytic dehydrogenation, the method of producing increased yields of substantially pure toluol while realizing maximum catalytic efficiency which comprises separating from a naphthenic straight run gasoline by fractional distillation a fraction boiling between about 190° F. and about 230° F., separating said 190° F. to 230° F. fraction into two fractions boiling between about 190° F. and about 200° F. and between about 200° F. and about 230° F. by fractional distillation, contacting the 190° F. to 200° F. fraction with an aluminum chloride catalyst under isomerization conditions, subjecting the 190° F. to 200° F. fraction together with the 200° F. to 230° F. fraction to a catalytic dehydrogenation, and recovering substantially pure toluol from the product.
2. In a process for the production of toluol from naphthenic straight run gasolines via catalytic dehydrogenation, the method of producing increased yields of substantially pure toluol while realizing maximum catalytic efficiency which comprises separating from the naphthenic straight run gasoline by fractional distillation a fraction boiling between about 190° F. and about 230° F., separating said 190° F. to 230° F. fraction into two fractions boiling between about 190° F. and about 200° F. and between about 200° F. and about 230° F. by fractional distillation, contacting the 190° F. to 200° F. fraction with a liquid aluminum chloride complex catalyst under isomerization conditions, subjecting

the 190° F. to 200° F. fraction together with the 200° F. to 230° F. fraction to a catalytic dehydrogenation, and recovering substantially pure toluol from the product.

3. In a process for the production of toluol from naphthenic straight run gasolines via catalytic dehydrogenation, the method of producing increased yields of substantially pure toluol while realizing maximum catalytic efficiency which comprises separating from a naphthenic straight run gasoline by fractional distillation a fraction boiling between about 190° F. and about 230° F., separating said 190° F. to 230° F. fraction into two fractions boiling between about 190° F. and about 200° F. and between about 200° F. and about 230° F. by fractional distillation, contacting the 190° F. to 200° F. fraction under isomerization conditions with a liquid catalyst prepared by combining anhydrous aluminum chloride with an aromatic kerosene extract, subjecting the 190° F. to 200° F. fraction together with the 200° F. to 230° F. fraction to a catalytic dehydrogenation, and recovering substantially pure toluol from the product.

4. In a process for the production of toluol from naphthenic straight run gasolines via catalytic dehydrogenation, the method of producing increased yields of substantially pure toluol while realizing maximum catalytic efficiency which comprises separating from a naphthenic straight run gasoline by fractional distillation a fraction boiling between about 190° F. and about 230° F., separating said 190° F. to 230° F. fraction into two fractions boiling between about 190° F. and about 200° F. and between about 200° F. and about 230° F. by fractional distillation, contacting the 190° F. to 200° F. fraction with an aluminum chloride catalyst under isomerization conditions, fractionally distilling said isomerized fraction to remove material boiling below about 200° F., subjecting the residual isomerized fraction together with the 200° F. to 230° F. fraction to a catalytic dehydrogenation, and recovering substantially pure toluol from the product.

5. In a process for the production of toluol from naphthenic straight run gasolines via catalytic dehydrogenation, the method of producing increased yields of substantially pure toluol while realizing maximum catalytic efficiency which comprises separating from a naphthenic straight run gasoline by fractional distillation a fraction boiling between about 190° F. and about 230° F.,

separating said 190° F. to 230° F. fraction into two fractions boiling between about 190° F. and about 200° F. and between about 200° F. and about 230° F. by fractional distillation, contacting the 190° F. to 200° F. fraction with an aluminum chloride catalyst under isomerization conditions, blending back the isomerizate with the naphthenic straight run gasoline to be fractionated subjecting the 200° F. to 230° F. fraction to a catalytic dehydrogenation, and recovering substantially pure toluol from the product.

6. In a process for the production of toluol from naphthenic straight run gasolines via catalytic dehydrogenation, the method of producing increased yields of substantially pure toluol while realizing maximum catalytic efficiency which comprises separating from a naphthenic straight run gasoline by fractional distillation a fraction boiling between about 190° F. and about 230° F., separating said 190° F. to 230° F. fraction into two fractions boiling between about 190° F. and about 200° F. and between about 200° F. and about 230° F. by fractional distillation, contacting the 190° F. to 200° F. fraction with an aluminum chloride catalyst under isomerization conditions, subjecting the 190° F. to 200° F. fraction together with the 200° F. to 230° F. fraction to a catalytic dehydrogenation, and recovering substantially pure toluol from the product by extractive distillation.

7. In a process for the production of toluol from naphthenic straight run gasolines via catalytic dehydrogenation, the method of producing increased yields of substantially pure toluol while realizing maximum catalytic efficiency which comprises separating from a naphthenic straight run gasoline by fractional distillation a fraction boiling between about 190° F. and about 230° F., separating said 190° F. to 230° F. fraction into two fractions boiling between about 190° F. and about 200° F. and between about 200° F. and about 230° F. by fractional distillation, contacting the 190° F. to 200° F. fraction with an aluminum chloride catalyst under isomerization conditions, subjecting the 190° F. to 200° F. fraction together with the 200° F. to 230° F. fraction to a catalytic dehydrogenation with a chromium oxide catalyst, and recovering substantially pure toluol from the product.
